UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 27,682, dated September 21, 1897.

Application filed August 13, 1897. Serial No. 648,177. Term of patent 3½ years.

To all whom it may concern:

Be it known that I, ADOLPH PETZOLD, a citizen of the United States, residing at the city of Philadelphia, State of Pennsylvania, 5 have invented and produced a certain new and original Design for a Rug, of which the following is a full, clear, and exact description, reference being had to the accompanying drawing, forming a part of this specification.

10 My design is adapted and intended for the surface ornamentation of a woven rug. Its distinguishing features comprise a rectangular floral border a, of irregular outline, forming a field-center b, within which is contained a diamond-pointed floral figure c, and within 15 the latter, at about the center thereof, is contained a smaller figure d of like character and contour.

I claim—

The design for a rug, substantially as shown 20 and described.

In testimony whereof I have hereunto affixed my signature this 8th day of July, A. D. 1897.

ADOLPH PETZOLD.
